FIG. 3.

UNITED STATES PATENT OFFICE.

HERMANN ZITZEWITZ, OF CHICAGO, ILLINOIS.

EMBOSSING-MACHINE.

SPECIFICATION forming part of Letters Patent No. 468,168, dated February 2, 1892.

Application filed April 18, 1891. Serial No. 389,400. (No model.)

To all whom it may concern:

Be it known that I, HERMANN ZITZEWITZ, a citizen of the United States, residing at Chicago, in the county of Cook and State of Illinois, have invented certain new and useful Improvements in Embossing-Machines, of which the following is a specification.

The present invention relates more especially to machines for embossing wood by means of a heated pattern-roller, which is pressed with great force against the wood or other material that is to be embossed and slowly rolled over it; and the object of the said invention is to improve such machines.

To this end the invention consists in certain features of novelty that are particularly pointed out in the claims hereinafter, and which are first fully described with reference to the accompanying drawings, which are made a part of this specification, and in which—

Figure 1 is a side elevation of the improved embossing-machine with some of the parts removed and others shown in section on lines hereinafter indicated. Fig. 2 is a sectional elevation, the section being mainly on the line 2 2, Fig. 1, but partly on other lines hereinafter indicated. Fig. 3 is a horizontal section in various planes hereinafter indicated. Fig. 4 is a detail view of one of the journal-boxes of the pattern-roller shaft.

The two castings forming the sides 1 and 2 of the base or pedestal are similar in outline and are bolted to the castings forming the back 3 and front 4, and each of said castings is bounded by a marginal flange for strengthening it. In the sides 1 and 2 are elongated openings 5, whose margins are parallel and vertical, save for a lateral re-

cision at 6. Journaled in suitable bearings supported by the sides 1 and 2 is a shaft 7, having a fast pulley 8, for receiving the driving-belt, and a loose pulley 9, to which said belt may be shifted to stop the machine. The belt is moved from one of these pulleys to the other by a shifter consisting of prongs 10, fixed to a rod 11, supported by the pedestal, so as to be capable of sliding endwise, and a lever 12, fulcrumed to a bracket-arm 13, projecting from the marginal flange of the side 1 of the

pedestal and connected at its lower end to said rod.

Loosely mounted upon the shaft 7 are two pinions 15 and 16 of different diameters, each of which has on its hub one member 17 of a double clutch, the other member 18 of which is secured to the shaft between said pinions by a spline and groove, so as to be incapable of turning upon the shaft, but capable of sliding longitudinally thereon, whereby one or the other of said pinions may be caused to turn with the shaft. The clutch is operated by means of a sliding rod 19, passing out through the side 1 of the pedestal and having at its outer end a handle 20 and a pair of levers 21, connected by a pin 22, occupying a circumferential groove in the sliding member 18.

Journaled below shaft 7 is a second shaft 23, to which is secured two pinions 24 and 25 of different diameters, gearing with the pinions 15 and 16, respectively. One end of this shaft projects outside of the side 1, and has secured to it a worm 26, which gears with a worm-wheel 27 secured to a vertical shaft 28 journaled in suitable bearings, supported by brackets 29 and 30 projecting from the side 1. To this vertical shaft 28 near its upper end is secured a worm 31, gearing with a worm-wheel 32 on a third horizontal shaft 33. The journal-bearings 34 of this shaft occupy the openings 5 and fit them so as to be capable of sliding vertically, but incapable of any considerable horizontal movement, and are held against longitudinal movement by lugs 34^a that engage the inner faces of the sides of the pedestal. Projecting downward from the under sides of these bearings are arms 35, having in their lower ends half-round sockets, which receive and are supported by horizontal pins 36, which latter are in turn supported by short arms or lugs 37, projecting from the upper side of a rock-shaft 38, journaled in half-bearings 39 and projecting beyond both sides of the pedestal. The bearings 39 occupy the openings 5, and are separately adjustable vertically by means of set-screws 30, tapped into lugs 41, projecting from the outside of the pedestal below said openings.

In Fig. 1 the wheel 27 and the worm 31 are

shown in section on the line 1 1, Fig. 3. In Fig. 2 the wheel 32, one of the boxes 34, one of the bearings 39, and the lug 41 beneath it, are shown in section in the vertical plane of the axis of said wheel. In Fig. 3 the worm 26 and the rear part of side 1 of the pedestal are shown in section in the horizontal plane of the axis of said worm.

Secured to the shaft 33 is a roller 45. A portion of this roller and portions of the shafts 33 and 38 are omitted from Fig. 2, in order to more clearly show the parts beyond. The top of this roller occupies an opening between the front and back halves of a table 46, which 15 is supported by flanges 47 on the inside of the pedestal. In Fig. 1 both halves of this table are indicated by dotted lines. In Fig. 2 the front edge of the rear half is seen in elevation, (excepting so much of it as is hid by 20 the roller 45,) and in Fig. 3 only one-half of the front half is seen. To it one or more adjustable guides 48 may be secured.

Secured to the tops of the sides 1 and 2 are standards 51 and 52, respectively, connected 25 at top by a beam 53. The standard 51 is omitted from Figs. 1 and 3, and the standard 52 is shown in Fig. 1 in elevation, and in Fig. 3 in horizontal section on the line 3 3, Fig. 1. In the front portion of each of 30 these standards is a vertical rabbet 54, in which rabbets fit tongues 55 on the respective ends of a cross-head 56, said tongues being confined in place by plates 57, (only one of which is shown in each of the figures,) 35 bolted to the front flanges of the standards. The cross-head 56 is shown in end elevation in Fig. 1, in front elevation in Fig. 2, and partly in plan and partly in section in Fig. 3, the plane of the section being irregular and 40 indicated by the line 3^a 3^b, Fig. 2. Projecting down from each end of it is a stout arm 58, strengthened by a flange 59, and carrying at its lower end the upper half 60 of a journal-box having a pair of perforated lugs 61 45 61, between which fits a corresponding perforated lug 62 on the lower half 63 of the box, the two halves being hinged together by a pin 64 and locked by a turn-bolt 65, screwed into the lower half and having an elongated 50 head spanning a slot 66 and bearing against the top of upper half. To open the box the head of the bolt is turned to a position parallel with the slot 66, and said slot being wide enough to receive it, the lower half can swing 55 away from the upper half. Journaled in these boxes is a shaft 67, to which may be removably secured a pattern-roller 68, having any desired design engraved upon its periphery.

60 69 is a curved sheet-metal shield which is situated over the pattern-roller and embraces its top side, said shield being supported by hangers 70, slotted at 71, for the passage of screw-bolts 72, by which they are secured to 65 the cross-head 56. The hangers are curved to conform to the exterior of the shield and

at their lower extremities they support a rigid bar 73. To this bar is adjustably secured by set-screw 74 an arm 75, and a block 76 is adjustably secured to said arm. To this block 70 is adjustably secured a second block 77, which supports one or more Bunsen burners 78, which may be supplied with gas through a rubber or other tube, a portion of which is shown at 79.

75 As before stated, this machine does its work by the combined action of heat and pressure. Before the piece of material to be embossed is inserted the embossing-roller is highly heated by means of the Bunsen burner, which 80 may be placed in any desired position with relation thereto, its heat being confined and made to traverse the periphery of the roller by the curved shield 69. In order that the roller shall be heated uniformly throughout 85 its entire circumference, it is turned continually, when not at work, by a belt 80, which embraces a grooved wheel 81 on an extension 82 of the shaft 67, and a pulley 83 on the driving-shaft 7, the two strands of the belt 90 being carried over separate idlers 84 85, journaled to a hanger 86, depending from a stud 87 on the outside of standard 52 and controlled by a hand-lever 88, fulcrumed at its lower end to the pedestal and connected by a 95 rod 89 with the lower end of said hanger. By moving this hand-lever in the direction of the arrow in Fig. 3 the belt will be tightened and the lever may be brought into engagement with one or another of a series of shoulders 100 90 on the edge of the top flange of the casting 2 for holding it in the desired position.

When the roller is heated sufficiently for use, the belt is slackened, so as to permit it to slip. The roller is then placed at the proper 105 distance from the table to admit beneath it the end of the piece of material to be embossed by turning a hand-screw 91, which is swiveled to the cross-head 56 and mounted in a suitable nut supported by the cross-beam 110 53. It is then turned by applying the hand to the wheel 81 until the design is brought to the desired position with relation to the strip to be embossed. The work-supporting roller 45 is then pressed firmly against the under 115 side of the strip, and being driven by the train of worm-gearing already described will feed the work through the machine, the pattern-roller being turned solely by its frictional contact with the work. To elevate or lower 120 the roller 45 it is only necessary to give the shaft 38 a part revolution in one direction or the other, during which its arms 37 and the arms 35 on the under sides of the boxes 34 operate as toggles. Its movement in opposite 125 directions is limited by lugs 91 and 92, formed on it and engaging lugs 93 and 94, formed on the sides 1 and 2 of the pedestal, respectively. To thus rock the shaft 38 the reduced end of a hand-lever 95 is inserted in an eye 96, formed 130 through a lug 97 on the projecting end of the shaft.

It is obvious that the rollers 45 and 68 may be transposed without departing from the spirit of my invention.

The machine may be used either with or 5 without heating the pattern-roller for embossing plastic compositions.

I am aware that it is not new to operate the platen of a press by means of toggles, and such is not the equivalent of my invention.

10 Having thus described my invention, the following is what I claim as new and desire to secure by Letters Patent:

1. In an embossing-machine, the combination, with a pair of rollers and a shaft supporting each, of a rock-shaft, toggles interposed between the rock-shaft and the shaft of one of the rollers, so as to exert their force in opposite directions directly against both of said shafts, and means for operating the rock- 20 shaft, substantially as set forth.

2. The combination, with a pair of rollers and a shaft supporting each, of movable boxes, in which one of said shafts is journaled, an arm projecting from each of said boxes, a 25 rock-shaft, and arms projecting from said rock-shaft, the arms of the journal-boxes and rock-shaft being jointed to form toggles, substantially as set forth.

3. The combination, with a pair of rollers 30 and a shaft supporting each, of a rock-shaft, toggles connecting said rock-shaft with the shaft of one of said rollers, and separately-adjustable bearings supporting the respective ends of said rock-shaft, substantially as 35 set forth.

4. The combination, with a pair of rollers and a shaft supporting each, of movable journal-boxes 34, in which the shaft of one of said rollers is journaled, means for guiding said 40 boxes, an arm 35, projecting from each, the rock-shaft 38, arms 37, projecting therefrom, and the pins 36, connecting the arms 35 and 37, substantially as set forth.

5. The combination, with the pedestal having 45 openings 5, a pair of rollers, and a shaft supporting each, of the removable journal-boxes 34, occupying said openings and having arms 35 projecting therefrom, the rock-shaft 38, passing through said openings and 50 having arms 37, supporting the arms 35, and means for rocking said rock-shaft, substantially as set forth.

6. The combination, with the pedestal having 55 openings 5, the roller 45, and the shaft 33, of the movable journal-boxes 34, occupying said openings, the arms 35, projecting from said boxes, the rock-shaft 38, passing through said openings and jointed to arms 35, the bearings 39 for said rock-shaft situated in said 60 openings, and the set-screws 40 for adjusting said bearings, substantially as set forth.

7. In an embossing-machine, the combina-

tion, with means for supporting the work and a pattern-roller, of a burner located in operative proximity to the outer periphery of said 65 roller, and a shield embracing said roller for confining the heat, substantially as set forth.

8. In an embossing-machine, the combination, with means for supporting the work, the embossing-roller, and means for heating it, of 70 a shield embracing said roller, and means for adjusting said shield toward and from said roller, substantially as set forth.

9. In an embossing-machine, the combination, with means for supporting the work and 75 an embossing-roller, of the shield 69, embracing the top side of said roller, the adjustable hangers 70, supporting said shield, and a burner, also supported by said hangers, substantially as set forth. 80

10. In an embossing-machine, the combination, with means for supporting the work and an embossing-roller, of the shield 69, the hangers 70, by which it is supported, the rod 73, the adjustable arm 75, the block 76, adjustably mounted on said arm, the block 77, adjustably connected to block 76, and the burner 78, supported by block 77, substantially as set forth. 85

11. The combination, with means for supporting the work, the pattern-roller, and its shaft, of a vertically-adjustable cross-head and boxes carried by said cross-head and in which said shaft is journaled, the lower halves of said boxes being hinged to the upper halves 95 and adapted to drop away from the shaft and thereby permit the upper halves to be lifted clear of the shaft by elevating the cross-head, substantially as set forth. 90

12. The combination, with means for supporting the work, the pattern-roller, and its shaft, of a vertically-adjustable cross-head and boxes carried by said cross-head and in which said shaft is journaled, said boxes consisting of the upper part 60, having opening 100 66 and perforated lugs 61, and lower part 63, having perforated lugs 62, pin 64, and turn-bolt 65, arranged substantially as set forth. 105

13. The combination, with means for supporting the work, of the standards 51 and 52, 110 having rabbets 54, the connecting-beam 53, the cross-head 56, having tongues 55, occupying said rabbets, the plates 57, bolted to the standards and overlapping said tongues, the hand-screw 91 for adjusting said cross-head, 115 the two-part journal-boxes carried by said cross-head, the shaft journaled therein, and the pattern-roller on said shaft, substantially as set forth. 120
